UNITED STATES PATENT OFFICE.

HARRY W. BROADY, OF BAYSIDE, NEW YORK, ASSIGNOR TO AMERICAN BALSA COMPANY, INC., A CORPORATION OF NEW YORK.

LOWERING AND RAISING APPARATUS FOR SHIPS' BOATS.

Application filed January 22, 1920. Serial No. 353,207.

To all whom it may concern:

Be it known that I, HARRY W. BROADY, a citizen of the United States, and a resident of Bayside, borough of Queens, county of Queens, and State of New York, have invented certain new and useful Improvements in Lowering and Raising Apparatus for Ships' Boats, of which the following is a specification.

10 This invention relates to improvements in lowering and raising apparatus for ships' boats.

In lowering ships' boats, and particularly in lowering nested boats, it is desirable to 15 provide double falls on a single davit or on each davit of a pair of davits in order to permit the swinging out and lowering of one boat and then without waiting to wind up the lowered falls, to swing the davit 20 inboard and utilize the other falls with the same davit arm for swinging out and lowering a second boat. When, however, double falls have heretofore been employed on a single davit arm, the loaded operating falls 25 were frequently fouled by the unloaded inoperative falls, and, particularly, parts of the loose outer falls, after being used to lower a boat, have often become jammed between the block and the upwardly running 30 parts of the inner loaded falls, bringing the end of the boat to which such falls are secured to an abrupt stop, while the opposite end is still being lowered. It has therefore been dangerous to utilize double falls on a 35 single davit arm.

The object of this invention is to enable the safe utilization of double falls in cooperation with a single davit arm and to maintain the parts of such double falls in 40 such spaced relationship to each other during use that the danger of fouling of the parts of one falls by the parts of the other falls will be greatly reduced, and a more rapid, economical and safe handling of life-boats, and particularly of nested life-boats, is made possible.

Another object of my invention is to provide for the double falls a spacing device 50 having a common, and preferably a centrally-disposed swinging connection with the davit arm whereby each of the falls when loaded will automatically assume a position in a perpendicular plane intersecting the said connection and the unloaded falls will be swung and retained away from

such perpendicular plane so as to prevent any contact or fouling of the loaded falls thereby.

With these and other objects in view, the invention comprises the combination of 60 members and arrangement of parts so combined as to co-act and cooperate with each other in the performance of the functions and the accomplishment of the results herein contemplated, and comprises in one of 65 its adaptations the species or preferred form illustrated in the accompanying drawings, in which:—

Fig. 1 is a side elevation of raising and lowering apparatus embodying my invention, 70 illustrating the manipulation of the top boat of two nested boats by a pair of davits;

Fig. 2 is a similar side elevation of a pair of davit arms showing the position of 75 the parts during the swinging out and lowering of the second or lower boat;

Fig. 3 is an enlarged side elevation of the upper end of the apparatus showing 80 the position of the falls during the swinging out and lowering of the first or top boat of two nested boats;

Fig. 4 is a similar side elevation showing the position of the upper part of the falls 85 during the swinging out and lowering of the second or lower boat; and

Fig. 5 is a front or outboard view of the top portion of a davit arm, yoke and falls forming part of my invention.

Referring now to these drawings, which 90 illustrate a preferred embodiment of my invention, 1 indicates one type of davit arm adapted to be used by me in carrying out my invention, a pair of these arms being shown in the operation of swinging out a 95 boat in Figs. 1 and 2. Each of the davit-arms illustrated is of the quadrant type having at its lower end a quadrant 2 rolling upon a rack 3 formed in a frame 4, and pivoted intermediate its ends at 5 on a nut 100 6 threaded on and movable rectilinearly and substantially parallel to the deck by means of a screw 7, journalled for rotary movement only in the frame 4.

To the upper end of the davit arm, I attach 105 a single attaching and spacing device for the double falls provided with a common centrally disposed connection with the davit arm. As illustrated, a yoke, substantially triangular in conformation, prefer- 110

ably comprises a spacing or cross bar 8 provided with a centrally-disposed hook 9 at the apex of the triangle and said spacing bar has arms 10 and 11 on opposite sides thereof for permitting the attachment, carrying and spacing of double falls 12 and 13 respectively. Said yoke is adapted to be swung about its connection with the end of the davit arm by the weight of the load as the davit arm swings from its inboard to outboard positions and vice versa, and the arm to which the load is secured will consequently assume a position in a perpendicular plane intersecting said connection and thus enable a ready lowering of the load in any suitable outboard position of the davit arm, while the other arm of the yoke to which the unloaded falls are attached will be swung away from such perpendicular plane and spaced from the loaded falls. The falls to which the load is attached thus control the swinging movement of the yoke about its connection with the davit arm, and the upper block of the unloaded falls will, by the weight of the load, be swung and retained at a suitable non-fouling distance from the perpendicular line occupied by the loaded falls.

The oppositely-disposed arms 10 and 11 of the yoke preferably extend radially of the connection between the davit arm and yoke at an acute angle to each other with an arc of substantially 90° therebetween, so that when the loaded falls assumes a position parallel or coincident with the perpendicular line along which the load is dropped, the unloaded falls will be swung in the arc of a circle and without undue friction a maximum distance at one side of the said perpendicular line, and the falls hanging from such unloaded arm will thus be retained in such spaced relation from the operating or loaded falls as to greatly reduce the possibility of a fouling contact between the same.

In the normal or inoperative position of the apparatus, the outer falls are connected to the top one of two nested lifeboats while the lower end 14 of the inner falls are fastened to a hook and cleat 15, 15^a on the middle portion of the davit arm so as to be out of the way.

After the top boat is swung out and lowered, the davit arm is brought inboard again without winding up the outer falls and the inner falls are then disconnected from the cleat 15 and secured to the lower lifeboat which is then swung out and lowered while the outer falls are hanging free.

The lower block of the unloaded falls will, as illustrated in Figs. 1 and 2, hang on the outside of the boat which is lowered by the inner falls and such unloaded falls being thus spaced at the upper and lower ends thereof from the operating falls will be en-

tirely out of the way and all possibility of fouling thereof will be greatly reduced.

In the preferred form of the invention shown, the upper end of the davit arm has an eye 1^a, the hook 9 is inserted therethrough, and the mouth 16 of the said hook is then closed by means of a pin 17 which is preferably passed, as shown, through the bill and shank of the hook so as to prevent a possible slipping of the hook out of the eye in its swinging movement or in the swinging movement of the davit.

Having described my invention I claim:—

1. In apparatus for lowering and raising ships' boats, the combination with a davit arm, of a falls-attaching device having a connection with the outer end of said davit arm; and also having elements spaced from each other for attaching double falls; double falls attached to said elements, said device being movable to swing each of said falls-attaching elements alternately into a plane substantially in vertical alignment with the said davit-connection while the other falls-attaching element is moved away from said plane. 80

2. In apparatus for lowering and raising ships' boats, the combination with a davit arm movable to swing in a vertical plane, of a falls-attaching device having a connection with said davit arm and movable to swing in a vertical plane about said connection, said attaching device having arms extending laterally to opposite sides of said connection, and double falls, one of which is connected to one end of one of said laterally-extending arms and the other to the opposite end of the other arm. 95

3. In apparatus for lowering and raising ships' boats, the combination with a davit arm provided at its upper end with an eye, a yoke provided with a centrally-disposed hook hooked in said eye to permit the swinging of the yoke inboard and outboard in relation to said upper end of the davit; yoke arms 105 on opposite sides of said hook and falls connected to each of such arms. 110

4. An apparatus for lowering and raising ships' boats, the combination with a davit arm provided at its upper end with an eye, a yoke provided with a centrally disposed hook hooked in said eye to permit the swinging of the yoke inboard and outboard in relation to said upper end of the davit; arms extending radially in opposite directions from the said connection, falls attached at one end to each of such yoke arms, and means on the lower portion of the davit arm for fastening the lower end of one of said falls. 115 120

5. In apparatus for lowering and raising ships' boats, the combination with a davit arm provided at its upper end with an eye, a yoke provided with a centrally-disposed hook hooked in said eye to permit the swinging of the yoke in the plane of movement of the 125 130

davit; yoke arms on opposite sides of said hook, falls connected to each of such arms and a pin for closing the mouth of said hook.

6. In apparatus for lowering and raising ships' boats, the combination with a pair of davits, double falls for each of said davits; an attaching device for the upper ends of the double falls carried by each davit at its upper end and movable to swing inboard and outboard of said upper end and means on

each davit arm intermediate its ends for fastening the lower end of a falls thereto.

In witness whereof, I have signed my name to the foregoing specification in the presence of two subscribing witnesses.

HARRY W. BROADY.
